UNITED STATES PATENT OFFICE.

JAMES E. ALLISON, OF ST. LOUIS, MISSOURI, ASSIGNOR TO GEORGE M. SEELEY, OF NEW YORK, N. Y.

SIGNALING SYSTEM.

No. 804,819.

Specification of Letters Patent.

Patented Nov. 21, 1905.

Application filed August 14, 1902. Serial No. 119,639.

To all whom it may concern:

Be it known that I, JAMES E. ALLISON, a citizen of the United States, residing at St. Louis, Missouri, have invented a certain new and useful Improvement in Signaling Systems, of which the following is a full, clear, and exact description, such as will enable others skilled in the art to which it appertains to make and use the same, reference being had to the accompanying drawings, forming part of this specification, in which—

Figure 1 is a view illustrating a plurality of track-signals in combination with the instrument in the home office. Fig. 2 is a diagrammatic view. Fig. 3 is a front elevation of the mechanisms supported in one of the track instruments, the front-plate of the casing being removed. Fig. 4 is a view, partly in section, at right angles to the view shown in Fig. 3. Fig. 5 is a detail view of the general character of that illustrated in Fig. 3, but showing the parts in another position. Fig. 6 is a top plan view of the mechanism illustrated in Figs. 3, 4, and 5, the top of the casing being removed; and Figs. 7 and 8 are fragmentary detail views illustrating modified constructions of the signal.

My invention relates to signaling systems, and is particularly applicable to suburban electrical railroads, although it is in no wise limited to such use.

My object is to provide means whereby the home office or the train despatcher can notify any car upon the track that the office desires to communicate with such car, there being means whereby after a car has been thus signaled communication can be had with the office.

To this end and also to improve generally upon systems of the character indicated and upon the apparatus employed in such systems my invention consists in the various matters hereinafter described and claimed.

Referring now more particularly to the drawings, 1 represents what may be termed the "sending instrument"—i. e., the instrument located in the home office—by means of which the signals along the track can be operated, the instruments located along the track being indicated by 2. These track instruments are located at convenient distances from each other, and each is provided with a signal which can be operated to attract the attention of the motorman or conductor of a car. I have here shown each track instrument pro-

vided with a signal-paddle 3, a signal-light 4, and a bell 4^a. The paddle of each track instrument is normally held in raised position and in the form of device shown in Fig. 1 the lamp 4 is extinguished and the bell-circuit is broken under normal conditions. When, however, it is desired to communicate with a car, the proper paddle is dropped to bring the same across the track, and at the same time the signal-lamp is lighted and the bell-circuit is completed. When the paddle falls and the lamp is lighted, a signal is given the home office, thus informing the despatcher or other official that the desired track-signal has operated. The signal-paddle, the lamp, and the bell remain in signaling condition until the conductor of the car or train has manually reset the paddle, extinguished the lamp, and broken the bell-circuit. A telephone, telegraph instrument, or other device 5 for communicating with the home office is located upon or near each of the track signaling apparatus, and I have here shown each telephone instrument along the track as located in the casing which supports the signaling apparatus. In Fig. 7 I have illustrated a device which includes a constantly-burning lamp, the shaft upon which the signal-paddle 3 is mounted also carrying a plate 6 of colored glass, which is thrown in front of the lamp when the paddle falls into signaling position.

I shall first consider the construction of the signaling apparatus located along the track. This is preferably mounted in and upon a boxing or casing 7, which can be of any suitable construction for containing the various mechanisms. Bolted or otherwise secured to the casing is a supporting-frame 8, having plates in which is journaled a horizontal shaft 9, the signal-paddle 3 being mounted upon said shaft to move therewith, and extending through a diametrical slot in the shaft is a bolt 10, which is normally forced into what may be termed "projected" position by means of a spring 11, fastened to the said shaft. Suitably supported upon the said frame 8 is a latch 12, which is controlled by the armature 13 of an electromagnet 14, the latch here shown being of a construction which is commonly used for controlling doors of apartment-houses and the like, and for this reason no further description of the said latch is thought to be necessary in this specification. When the signal-paddle is thrown into raised position,

the bolt 10 is engaged by the said latch 12 and the shaft 9 and its paddle 3 are locked in normal position, being held in such position against the force of a spring 15, coiled about 5 the said shaft, one end of said spring being connected to the shaft and its other end being held upon the frame 8 in a manner which will be well understood. In addition to the arm carrying the signal-paddle 3, the shaft 9 is 10 provided with an arm 16, to which is connected a cord or rod 17, adapted to be grasped by the operator for the purpose of throwing the shaft into normal position after the same has been tripped.

15 Upon suitable cross-bars 18 upon the frame 8 are oppositely-located spring contact-fingers 19, which are included in the circuit controlling the lamp 4, and extending transversely through an arm 20 upon the shaft 9 and insulated 20 from said arm is a cross-bar 21, whose ends are adapted to engage the said spring-contacts 19, and thus complete the light-circuit. The said bars 18 also support spring contact-fingers 19^a, which are included in and 25 control the bell-circuit, a cross-bar 21^a upon the arm 20 and insulated therefrom co-operating with said fingers to complete the said circuit when the paddle moves into signaling position. The parts are so arranged with 30 relation to each other that when the shaft 9 is in set position—i. e., when the signal-paddle is in its normal position—the cross-bars or connectors 21 and 21^a are out of engagement with the respective sets of spring-fingers 19 and 19^a; but when the shaft has been partially 35 rotated to bring the paddle 3 in signaling position the said cross-bars or connectors lie between the said spring-fingers, and thus complete the said circuits. The movement of the 40 shaft 9 can be limited in any suitable manner, and I have here shown the parts so arranged with relation to each other that the said arm 20 engages one of the side-bars of the frame 8 when the shaft is thrown into set position, 45 and a plate 22, connected to said arm and shaft, engages the opposite side bar of the said frame when the shaft moves into position to throw the signal-paddle and to light the lamp and ring the bell.

50 Suitably supported upon the frame 8 is a signaling mechanism for transmitting a signal to the home office when the shaft 9 has been rotated to throw the signal-paddle and to complete the light and bell circuits. The signaling apparatus here employed is indicated 55 at 23 and includes a notched disk 24, which co-operates with a spring contact-finger 25, said disk being rotated through a train of gears 26, driven from a spring-actuated shaft 27, the 60 spring being indicated at 28. The mechanism just described is merely the usual mechanism of a telegraph-call and will therefore be readily understood. Fixed upon the shaft 27 is a gear 29, which meshes with a gear 30, loosely 65 mounted upon the shaft 9. Extending dia-

metrically through a second slot in the said shaft 9 is a bolt 31, which is slideable in the said slot, said bolt being normally held in operative or projected position by means of a spring-plate 32, fastened to the shaft 9. The 70 forward end of this bolt lies behind and in engagement with a lug 33 upon the face of the loose gear 30 when the parts are in normal position, so that when the shaft 9 is tripped and turned to throw the signal-paddle the 75 loose gear 30 turns with said shaft and through the gear 29 winds the spring 28. Projecting from the side of the bolt 31 is a pin 34, which as the bolt is moved by the rotation of the shaft 9 engages a cam projection 35 in its path 80 of movement, whereby the said bolt is retracted against the force of the spring 32 to carry the bolt out of engagement with the lug 33, this retraction of the bolt occurring at almost the end of the movement of the shaft 85 9, said shaft having sufficient further movement to carry the bolt beyond the rear end of the lug 33, and thus prevent operative engagement between the said bolt and lug as soon as the pin has ridden over the cam 35. 90 As soon as the bolt has been carried out of engagement with the said lug the spring 28 asserts itself and the shaft 27 commences to rotate in the direction opposite to that in which it has been rotating, the signal mechanism 23 being thus thrown into action in a manner which will be readily understood. By this reverse rotation of the shaft 27 the gear 30 is rotated about the shaft 9 until the lug 33 95 engages a suitable stop 36, whereupon the signaling mechanism 23 ceases to operate, and the gear 30 and said signaling mechanism come to rest in their normal positions. When the shaft 9 is turned backwardly to reset the same, the bolt 31, which has a cam outer end, slides along the lug 33 until it clears the same, and said bolt is then forced into projected 100 operative position by means of the spring 32, the parts being then ready for a subsequent 105 operation of the apparatus.

The circuit through the magnet 14, which controls the latch 12, is controlled by a switch apparatus 37, conveniently supported in the casing 7. This switch apparatus is somewhat 110 of the general type of a telegraph-sounder and includes a supporting-arch 38, between the legs of which is pivotally mounted a lever 39, which has an armature 40 extending across the same and co-operating with electromagnets 41, the upward movement of the lever being 115 limited by means of an arm 42, which extends over its free end and is provided with a set-screw 43. Upon the post 44, from which the said arm 42 extends, is pivoted a disk 45, of fiber or other insulating material, said disk 120 extending in a plane substantially parallel to the plane in which the lever 39 oscillates and having a pin 46 of conducting material embedded therein and extending from the metallic pivot-pin 47 of the disk to the periphery 125 130

thereof. A conducting-plate 48 of resilient material bears against the periphery of the said disk and is thus adapted to make contact with the said pin. A plate 49, having 5 peripheral teeth, is fastened to the said disk 45 upon its outer side, (i. e., the side removed from the lever 39,) and upon the other side of said disk is a ratchet-plate 50. A spring-operated pawl 51 is pivotally supported upon 10 the end of the lever 39 and co-operates with the ratchet-teeth of the plate 50 for turning the disk 45 by a step-by-step movement, and a spring-operated locking-dog 52 co-operates with the ratchet-teeth of the said plate 50 to 15 prevent backward movement of the same. A rock-shaft 53 is journaled upon the supporting-post 44 and extends transversely the same, one end of said rock-shaft carrying an arm 54, which has a projection 55, adapted to be 20 thrown under a tooth of the plate 49, and to thus limit the forward movement of the disk 45. Upon the opposite end of the said rock-shaft is a radially-extending finger-plate 56, which lies between two set-screws 57 and 58, 25 supported upon a frame 59, carried by the lever 39. Thus whenever the lever is thrown downwardly by the action of the magnets 41 the pawl 51 throws the plate 45 forward one step, a tooth slipping by the locking-pawl 52 30 and the rock-shaft 53 being rocked, by means of the screw 57, to throw the projection 55 into the path of movement of one of the teeth upon the plate 49. When the current is cut off from the said magnets and the lever rises 35 under the action of the spring 60, the screw 58 engages the under side of the finger-plate 56, and the shaft 53 is thus rocked to carry the projection 55 out of the path of movement of the teeth upon the plate 49, the pawl 51 being 40 brought into position to engage a new tooth. The device is positive in its action, and the movement of the disk through only one step at each operation of the lever is insured, as the projection 55 limits the forward movement of the said disk. Backward movement of 45 the disk is prevented by the locking-pawl 52.

Two relays 61 and 62 are supported in the casing 7, as are also local cells or a local battery 63. These relays can be of any suitable 50 construction, and their purpose will be more fully hereinafter described.

An instrument used at the home office called a "sounding instrument" is illustrated in Fig. 2 as including a dial 67, being divided into a 55 number of spaces equal to one more than the number of track-signals, the extra one being provided to be marked "0," and the others are numbered consecutively to correspond to the track-signals. In rear of the dial is an annular contact-plate 69, whose periphery is notched, as shown in Fig. 2. Secured on said contact-plate, but insulated therefrom, is a contact-arm 70; said arm lying upon the outer side of said plate.

82 indicates a sounder or signaling appa-

ratus, here shown as a telegraph-sounder of usual construction, this device being conveniently supported upon a bracket 83 upon the casing 64.

Referring now more particularly to Fig. 2, 70 it will be seen that the notched contact plate or dial 69 is in electrical connection with a battery or other source of electrical energy 84, while adjacent to the dial 69 is a spring contact-finger 85, which co-operates with the 75 periphery of the said dial, the notches 86 of the dial being of such size that there are times when the said finger simply lies in a notch, and thus does not engage the said plate. A line-wire 87 extends from the said finger, and 80 connected to the said line-wire is a wire 87^a, which extends to relay-magnet 61, the other pole of said magnet, and the pole of the battery 84 not directly connected to the contact-disk 69, being conveniently grounded. The 85 battery 63 in each track signaling apparatus has one pole connected by a wire 88 with one pole of the magnet of the switch 37, and the other pole of the magnet of said switch is connected to the armature 61^a of the relay 61 by 90 a wire 89. The opposite pole of the said battery is connected by a wire 90 with a terminal 91 with which the said armature 61^a (or some suitable conducting member carried thereby and connected to the wire 89) is adapted to make contact when the said relay-magnet is energized and the armature is attracted. A second battery 92 at the home station has one pole grounded by the wire 93 and its other pole connected to the dial 67 by means of a 100 wire 94, which is connected to the magnets of the sounder 82, intermediate the said battery and the said dial. The contact-arm 70 is in electrical connection with a line-wire 95, from which a wire 96 leads to the spring contact-finger 25 of the signaling mechanism 23 in each casing 7, and a wire 97 connects the contact-disk which co-operates with the said finger with one pole of the magnet of the relay 62, the opposite pole of said magnet being 105 grounded through the wire 98. The armature 62^a of the relay 62 (or some contact member carried by the said armature) is connected by the wire 99 with one pole of the latch-magnet 14, the other pole of said magnet being connected by the wire 100 with the metallic shaft or pivot-pin upon which the switch-disk 45 is mounted, and the spring contact finger or plate 48 is connected by the wire 101 with one pole of the local battery 63, the other pole of said battery being connected by the wire 102 with a terminal 103, adapted to be 110 electrically engaged by the armature 62^a when the said armature is attracted by its magnet, said wire 102 being conveniently connected 115 to the before-mentioned wire 88.

The light and bell circuits, which are indicated at 104 and 104^a, can receive their energy from any suitable source and are merely 120 broken for the purpose of enabling the same 130

to be completed by means of the before-mentioned conducting cross-bars 21 and 21^a.

It will of course be understood that each track signaling apparatus is provided with light and bell circuits and is also provided with a local battery 63, with relays 61 and 62, with a switch mechanism 37, and with a latch-magnet 14, the wires 87 and 95 being line-wires leading from the home station or despatcher's office and wires 87^a and 96 leading at each track signaling apparatus from the respective wires 87 and 95 to the relays 61 and 62 of each track signaling mechanism. The various track signaling mechanisms are numbered to correspond to the numbers upon the dial 67, and the disk 24 of each of said mechanisms is provided with the proper number of notches to cause the sounder 82 to sound a number of times corresponding to the number of the particular mechanism which is being operated. The disks 45 of the various track mechanisms are so set that each, in order to bring its conducting-pin 46 in engagement with the contact-plate 48 when the circuit including the said pin and plate is energized, must be moved through a number of steps corresponding to the number of the particular track signaling mechanism in which it is included. For example, in track signaling mechanism No. 1 the disk 45 will be so set that one depression of the lever 39 of the switch mechanism serves to throw the said pin into engagement with the contact-plate 48. The disk 45 in track mechanism No. 2 is so set that the lever 39 must be twice depressed in order to cause contact between the said pin and the said plate, &c.

We pass now to a consideration of the operation of the device. Under normal conditions all of the signal-paddles 3 are in raised position, the bell-circuits are broken, and the lights are extinguished, or if the type of device shown in Fig. 7 is employed a white light shows, the disk of colored glass being in such position that it does not cover the said light. All of the circuits are broken, for the contact-disk 69 is held at rest in such position that the contact-spring 85 lies in one of the notches of the said disk. There is no connection between the dial 67 and the contact-arm 70. The armatures 61^a and 62^a are held by their springs away from their terminals 91 and 103, and the various switch mechanisms 37 have their disks 45 in normal position, with the contact-pins 46 out of engagement with the respective plates 48. The contact-fingers 25, however, engage the signaling-disks 24 and make contact therewith. We will assume that the despatcher desires to operate track-signal No. 5. The contact-disk 69 and contact-arm 70 may be carried forwardly until the contact-arm engages the conducting-pin 80, when the parts will be brought to rest. Between the time that the mechanism has been thrown into operation and the time it is stopped, as just in-

dicated, five of the teeth upon the contact-disk 69 will have engaged the contact-finger 85, and the relay-magnet 61 of each track signaling mechanism will thus have been energized five times. Therefore the magnet 70 of the switch mechanism 37 of each track signaling apparatus will have been energized five times, whereby the disk 45 of each switch mechanism will have been thrown through five steps. The disk 69 will then come to rest in such position that the contact-finger 85 lies in one of its notches, and therefore the current is broken as soon as said disks stop. No current passes along the wire 95 until the contact-arm 70 is brought to rest 80 against the conducting-pin 80. Thus it will be seen that although the conducting-pin 46 of the track signaling mechanism No. 1 engaged the plate 48 when the first tooth of the contact-disk 49 engaged the finger 85 the latch-magnet 14 of the track signaling mechanism No. 1 was not energized. The conducting-pins 46 of track signaling mechanisms Nos. 2, 3, and 4 were successively brought into engagement with their coöperating contact-plates 48; but for the reason just given no current was conducted to the latch-magnets. Of course although the contact-pins of switch mechanism Nos. 1, 2, 3, and 4 were brought into successive engagement with their coöperating contact-plates 48 each conducting-pin 46 was thrown out of engagement with its coöperating contact-plate 48 upon the movement of the lever 39 next following the movement by means of which a particular pin and plate had been brought into engagement. As the fifth tooth of the contact-disk 69 engaged the finger 85 the switch-dial of track signaling mechanism 5 was brought into such position that its conducting-finger 46 engaged its contact-plate 48, and as the contact-arm 70 came to rest against the conducting-pin 80 after the said fifth tooth of the contact-plate 69 had engaged the finger 85 and before the sixth tooth of said plate engaged said finger the circuit including the latch-magnet 14 of track signaling mechanism No. 5 is now complete except for the break between terminal 103 and the armature 62^a. As soon, however, as contact-arm 70 engages the pin 80 the circuit is completed through the relay-magnet 62, and the circuit through the latch-magnet is therefore completed, and the signal-paddle is released, the light and bell circuits being completed as the said paddle falls. Through the mechanism heretofore explained the signaling apparatus 23 operates as soon as the paddle falls, and the sounder 82 at the despatcher's office is operated to inform him that that particular track-signal has been thrown. After the sounder has operated and the despatcher is satisfied that the desired signal has been thrown the pin 80 is removed from the hole in the dial to the contact-disk 69, and contact-arm 70 is moved through the 130

remainder of the revolution which has been partly made, the parts coming to rest at the proper time. During the revolution of said disk 69 the teeth of said disk have engaged 5 the contact-finger 85, and at each engagement of said parts every switch-dial 45 has been moved one step, so that when the contact-disk and the other parts of the sounding instrument reach normal zero position each 10 switch-dial stands in its normal position ready for a second operation. Although during this action the switch-dial of each track signaling mechanism of a number higher than that which has been operated is brought into 15 such position that the conducting-pin 46 engages the contact-plate 48, the latch-magnets of these several mechanisms are not operated, for the reason that no current flows through the circuits including the said latch-magnets 20 except when the conducting-pin 80 connects the dial and the contact-arm 70. It will thus be seen that the circuit including each latch-magnet is broken at two points, and these 25 two points of a circuit are simultaneously closed only in the particular track signaling mechanism desired to be operated.

A telephone or corresponding device 5 is located at or near each track signaling mechanism, so that as soon as a conductor reaches 30 a point at which a signal is thrown he can communicate with the home office. The telephones at the track signaling mechanisms and the telephone 105 at the home station can be conveniently connected to the line-wires 87 35 and 95 in a manner which will be perfectly obvious.

I am aware that many minor changes in the construction, arrangement, and combination of the several parts of my device can be made 40 and substituted for those herein shown and described without in the least departing from the principle and nature of my invention.

As shown in Fig. 8, the light upon the supporting-case can be omitted and a row of lamps can be placed along the paddle, said lamps preferably being lighted at all times.

Having thus described my invention, what I claim as new, and desire to secure by Letters Patent is—

1. In a system of the character indicated, a plurality of signals, an operating mechanism for each of said signals, a source of energy local to each said operating mechanism, a circuit local to each said operating mechanism and including the same and said source of energy local thereto, a switch in each of said local circuits, a switch-operating mechanism for each said switch, a line-circuit including all of said switch-operating mechanisms and receiving its energy from a source independent of said local sources of energy, a device in said line-circuit for controlling the same, a second switch in each of said local circuits, said second switches being adapted to be brought into operative positions at dif-

ferent times with respect to each other, a second circuit local to each of said signals, an operating mechanism for each of said second switches and located in the respective said second local circuit, a switch in each of said second local circuits, a switch-operating mechanism for each of said last-mentioned switches, a second line-circuit including all of said last-mentioned switch-operating mechanisms and receiving its energy from a source independent of said local sources of energy, and a device in said second line-circuit for controlling the same; substantially as described.

2. In a system of the character indicated, a plurality of signals, an operating mechanism for each of said signals, a source of energy local to each said operating mechanism, a circuit local to each said operating mechanism and including the same and said source of energy local thereto, a switch in each of said local circuits, a switch - operating mechanism for each said switch, a line-circuit including all of said switch-operating mechanisms and receiving its energy from a source independent of said local sources of energy, a device in said line-circuit for controlling the same, a second switch in each of said local circuits, said second switches being adapted to be brought into operative positions at different times with respect to each other, a second circuit local to each of said signals and deriving its energy from said local source of energy, an operating mechanism for each of said second switches and located in the respective said second local circuit, a switch in each of said second local circuits, a switch-operating mechanism for each of said last-mentioned switches, a second line-circuit including all of said last-mentioned switch-operating mechanisms and receiving its energy from a source independent of said local sources of energy, and a device in said second line-circuit for controlling the same; substantially as described. 80 85 90 95 100 105

3. In a system of the character indicated, a plurality of signals, an operating mechanism for each of said signals, a source of energy local to each said operating mechanism, a circuit local to each said operating mechanism and including the same and said source of energy local thereto, a switch in each of said local circuits, a switch-operating mechanism for each said switch, a line-circuit including all of said switch-operating mechanisms and receiving its energy from a source independent of said local sources of energy, a device in said line-circuit for controlling the same, a second switch in each of said local circuits, said second switches being adapted to be brought into operative positions at different times with respect to each other, a second circuit local to each of said signals, an operating mechanism for each of said second switches and located in the respective said second local circuit, a switch in each of said second local circuits, a switch-operating mechanism for each of said 130

- last-mentioned switches, a second line-circuit including all of said last-mentioned switch-operating mechanisms and receiving its energy from a source independent of said local sources of energy and also independent of said source of energy which supplies said first-mentioned line-circuit, and a device in said second line-circuit for controlling the same; substantially as described.
- 10 4. In apparatus of the character indicated, a signal, operating mechanism therefor, a normally-open circuit controlling said mechanism, a station-signal in said circuit, a signal-sending mechanism in said circuit and provided with a circuit-breaker normally in circuit-forming position, means for closing said circuit to cause operation of said first-mentioned signal, and means whereby said first-mentioned signal by its operation causes signal-sending operation of said circuit-breaker of said signal-sending mechanism; substantially as described.
- 15 5. In a system of the character indicated, a signal, means for operating the same, a part movable upon operation of said signal, and an answering-back mechanism including a second signal, a driving means, a loosely-mounted gear, operative connection between said gear and said second signal, connection between said gear and said driving means for placing the latter in driving condition by operation of the former, means for operatively connecting said movable part and said gear, and means for automatically breaking said connection; substantially as described.
- 20 6. In a system of the character indicated, a signal, means for operating the same, a part movable upon operation of said signal, and an answering-back mechanism including a second signal, a driving means, a loosely-mounted gear, operative connection between said gear and said second signal, connection between said gear and said driving means for placing the latter in driving condition by operation of the former, a member upon said movable part and engaging said gear, and a projection in the path of movement of said member for breaking said engagement; substantially as described.
- 25 7. In a system of the character indicated, a signal, means for operating the same, a shaft rotatable upon operation of said signal, and an answering-back mechanism including a second signal, a driving member, a gear loosely mounted upon said shaft and connected to said driving member for placing the latter in driving condition, a bolt upon said shaft engaging said gear, a projection in the path of travel of said bolt for breaking said engagement, and operative connection between said

gear and said second signal; substantially as described.

8. In a switch of the character indicated, a rotatable disk, a contact member thereon, a second contact member coöperating with said first-mentioned contact member, a reciprocating lever, pawl-and-ratchet connection between said lever and said disk for driving the latter, teeth upon said disk, an arresting-pawl adapted to coöperate with said teeth to limit the forward movement of said disk, operative connection between said arresting-pawl and said lever, and means for adjustably regulating the throw of said arresting-pawl; substantially as described.

75 9. In a switch of the character indicated, a rotatable disk, a contact member thereon, a second contact member coöperating with said first-mentioned contact member, a reciprocating lever, pawl-and-ratchet connection between said lever and said disk for driving the latter, teeth upon said disk, a pawl adapted to coöperate with said teeth to limit the movement of said disk, and adjustable operative connection between said pawl and said lever; substantially as described.

80 10. In a switch of the character indicated, a rotatable disk, a contact member thereon, a second contact member coöperating with said first-mentioned contact member, a supporting-post, a pawl pivotally supported upon said post, teeth upon said disk with which said pawl engages to limit the movement of the disk, pawl-and-ratchet connection between said lever and disk for driving the latter, a finger extending from said first-mentioned pawl, and parts carried by said lever and engaging opposite sides of said finger; substantially as described.

85 11. In a switch of the character indicated, a rotatable disk, a contact member thereon, a second contact member coöperating with said first-mentioned contact member, a supporting-post, a pawl pivotally supported upon said post, teeth upon said disk with which said pawl engages to limit the movement of the disk, pawl-and-ratchet connection between said lever and disk for driving the latter, a finger extending from said first-mentioned pawl, and adjustable parts carried by said lever and engaging opposite sides of said finger; substantially as described.

90 In testimony whereof I hereunto affix my signature, in the presence of two witnesses, this 11th day of August, 1902.

JAMES E. ALLISON.

Witnesses:

GALES P. MOORE,
GEORGE BAKEWELL.
